PLANT FOR THE MANUFACTURE OF
BRONZE COLORS

Erwin Kramer, Berlin, Germany, assignor to the
firm of "Hartstoff-Metall A. G. Hametag," Ber-
lin-Kopenick, Germany

Application August 9, 1934, Serial No. 739,121
In Germany August 9, 1933

5 Claims. (Cl. 134—76)

My invention relates to the manufacture of metal powders, more particularly bronze powders, which are composed of extremely fine very small leaves or laminæ, and which when used together with a suitable lacquer, or the like, constitute a paint of excellent covering capacity.

The plant or machine embodying the present invention permits the starting material, i. e. small pieces of the metal, chips, coarse powder, foil waste and the like, to be transformed into finished polished bronze powder in one continuous operation without any danger of explosion.

In the machine according to my invention the starting material is first stretched or hammered out so as to become laminated, whereupon the fine particles are conveyed by a current of air into a sifter in which the finished particles are separated from the unfinished ones. These latter particles are returned to the laminating device in order to be hammered a second time, whereas the finished particles are carried further into a device in which they are separated from the air; this device may be a so-called cyclone separator. The separated particles, i. e. the bronze powder, are then conveyed to a suitable polishing machine.

While the bronze particles are conveyed from the sifter to the polishing machine air is excluded so that oxidation, heating and ignition resulting in an explosion are completely prevented. Extraordinarily fine bronze powder is particularly inclined to self-ignition when brought into contact with air or oxygen. The hammered and laminated particles are conveyed while hot from the one manufacturing phase to the other which is important inasmuch as the fat employed in the hammering phase does not become cold and can effectively be used in the polishing machine.

The polishing operation consists in subjecting the fine particles to the action of brushes, and since there is, practically, no oxide at all upon the particles treated according to this invention, the final product, i. e. the finished bronze powder, has a very bright lustre.

The amount of fat supplied prior to, or during, the hammering and laminating operation can be reduced to a minimum, because the oxidation risk and the ignition danger are greatly diminished, and it is, therefore, possible to produce a bronze powder very poor in fat and, therefore, particularly useful for printing purposes.

Because the bronze powder requires a certain degree of heat while it is being polished, and heat is also required for the proper distribution

of the fat, the cooling down of the bronze while it passes through the machine, should be prevented as much as possible and it is, therefore, important to convey the bronze particles directly from the sifter to the polishing machine, with complete exclusion of air. Also time and labor are saved.

When bronze powders for pyrotechnical purposes are produced, in which case not only the thinness of the laminations or foil particles, but also their smallness must be considered, a portion of the work of comminuting the already sufficiently thin particles can be carried out in the polishing machine, which renders the operation more economical. That is made possible, because only very little fat is required to hammer or laminate the foils, and because no additional supply of fat in the polishing machine takes place, the particles are thoroughly torn.

To reduce or entirely prevent oxidation is important not only in the manufacture of easily ignitable aluminium bronze, but also as regards bronzes from other metals, for instance the so-called gold-bronzes which are made from base metals. In these bronzes oxidations cause changes of the colors or tints, which changes generally are very undesirable since they impair the value of the bronzes.

Another important feature of my improved plant resides in this, that the conveying air current circulates only through the hammering machine, the sifter and the cyclone separator, but not through the polishing machine, because otherwise the metal particles would be whirled up which would be detrimental to the action of the brushes of this machine.

On the other hand, it is important that powders having a tendency to self-ignition receive a protective film of an oxide prior to leaving the polishing machine. This is a requisite especially if the formation of an oxide film has been intentionally diminished during the hammering phase. Therefore, care must be taken that a sufficient amount of oxygen is supplied to the polishing drum for that purpose. However the flow of the oxygen or oxygen containing gas through that drum is so controlled that the particles of the bronze are not whirled up. The gas flows through the drum in counter-direction to the direction of the bronze particles, and from the drum it is led through the sifter etc., the gas leaving the plant finally at the place when the material is fed to the hammering device, so that there is a true counter-current between the gas and the metallic particles. The gas mixtures leaves the

main content of the oxygen which it contains in the polishing drum, while in its further course it becomes poorer and poorer in oxygen.

My improved plant for the manufacture of bronze powders is shown diagrammatically and by way of illustration on the accompanying drawing on which Figure 1 is a sideview of the complete plant, only the lower right-hand corner of the figure being shown in axial section. Figure 2 is a transverse section in the plane A—B of Fig. 1, and Figure 3 is a transverse section in plane C—D of Fig. 1.

On the drawing, 1 (Figs. 1 and 2) denotes a horizontally disposed rotary drum which is supported on rolls 3 and 4 by which it is rotated. Within said drum are axially arranged radially directed partition walls 1^a, by which small steel balls 2 are carried upwardly as the drum is being rotated. The drum contains the metallic pieces, etc. to be hammered and comminuted (laminated) which is effected by the steel balls as they continually fall down upon the metallic pieces carried likewise round by the partition walls 1^a. The rolls 3 and 4 are rotated by any suitable means (not shown).

The pipe 5 for supplying the material to be treated and the pipe 6 for withdrawing the treated material are, of course, stationary, but at their ends where they join the drum 1, they are packed to prevent any communication with the outer air.

The material to be treated is contained in an upright funnel-shaped receptacle 7 which is connected at its lower end with the pipe 5 by means of a branch 9 of this pipe and by means of a so-called sluice 8 in which a distributing member is rotated by any suitable means whereby the material is fed in uniform amounts through the pipe 5 into the drum.

14 denotes a fan which is likewise connected with the pipe 5 by means of a branch 12 of the same and a pipe 13. The current of air produced by the fan and flowing through the drum carries along with it the fine particles of the material to be treated, the mixture then passing on through the pipe 6 into the sifter 10 which is connected at its lower end with the pipe 5 by means of a sluice 11 resembling the sluice 8 and being likewise continually rotated. Those comminuted metal particles which are not yet sufficiently small are returned to the drum 1 through the sluice 11 and the pipe 5, whereas the sufficiently fine particles are conveyed from the sifter 10 through the pipe 16 which terminates in the separator 17, a so-called cyclone separator.

At its bottom, the separator 17 is also furnished with a rotary sluice 19, by which the separated particles are conveyed through a pipe 21 to the polishing drum 20 which is stationary and in which rotate axially disposed brushes 24 that contact with the inner wall of the drum. These brushes are carried by a shaft 23 having at one of its outer ends a pulley 22 by means of which the brushes are rotated. The bronze particles pass through the polishing drum from the left-hand end (Fig. 1) to the right-hand end, and the finished bronze powder leaves the drum through the branch pipe 25 dropping into a collecting receptacle 26.

If oxygen or an oxygen-containing gas is used, it is introduced into the drum 20 through the pipe 28. It is sufficient to use nitrogen containing a few percent of oxygen. The gas or gas mixture flows through the polishing drum and then further into the separator cyclone 17 either through

the sluice 19 or through an auxiliary pipe 37; then the gas or gas mixture flows through the pipes 15, 13, 12 and 5 into the drum 1 and takes part in the circuit on the ways 6, 10 and 11.

From the branch 9 extends an upwardly slanting branch pipe 34 which communicates with a pressure-regulating device 35.

Suitable to the purpose, the plant is held under a certain pressure slightly above the atmospheric pressure, say an excess of pressure of a few centimeters of water-column, in order to completely prevent entrance of atmospheric air even if leakages should arise.

Irrespective of whether the fan 14 runs at a higher or lower speed, the pressure regulator 35 permits only the predetermined amount of gas to escape. In the practical operation of the plant the gas may be introduced into the polishing drum through the pipe 28 with a pressure of about 50 mm. of mercury, whereas the regulator 35 is adjusted for a pressure of about from 38 to 40 mm. The drop of from 10 to 12 mm. between the inlet and the outlet is sufficient to drive an appropriate amount of gas through the plant. In many cases the fan 14 need run only temporarily, for instance with a pressure of 100 mm. of water column. Also this manner of operation does not vary the amount of gas discharged through the outlet valve 36, because the regulator 35 maintains an exit pressure of 40 mm. of mercury. On the other hand also the supply of the gas entering through the pipe 28 with a pressure of about 50 mm. of mercury is not disturbed, because the conveying air does not circulate through the polishing drum 20 which drum communicates with the suction side of the fan through the separator 17.

With this manner of supplying the gas no gas need be supplied through the separate gas supply pipe 30 which terminates in the pipe 15. Where such a special pipe is provided, it may be closed if the other way mentioned is used.

The required amount of fat may be supplied through a pipe 27 terminating in the pipe 5 where it is forked. It is, however, also possible to apply the fat directly to the metal pieces in the feeding receptacle 7.

For supplying fat to the polishing drum 20 a separate vessel 32 is connected with the pipe 21 by means of a branch 31 into which a regulating valve may be inserted. Preferably, however, a rotary sluice 33 is used instead of said valve, the sluice supplying the fat in a uniform manner. It is also possible to connect the pipe 31 directly to the drum 20.

I wish it to be understood that the drawing shows merely a preferred embodiment of the plant. Various changes in the details may be made without constituting a departure from the invention. The rotary sluice 19 at the foot of the separator 17 may, for instance, be dispensed with, if a continuous and uniform supply of the bronze powder to the polishing drum is not thought indispensably requisite. It is at any rate advantageous to make use of a polishing machine through which the powder passes uninterruptedly, as in the case illustrated in the drawing.

The tube 34 is preferably provided with a filter in order to prevent metal particles from passing therethrough. Tubes like 34 may be provided, of course, also at other places of the plant, if that is desired.

Because of the gas supply being provided at the suction side of the fan a certain slight pressure above atmospheric pressure exists also at

the place of lowest pressure, and by the use of the inert gas atmosphere within the plant the possibility is afforded to work with a temperature between 50 and 100° C. As inert gas a gas resulting from the combustion of illuminating gas or from oil or coal etc. may be used, if that gas contains from 2 to 4% of oxygen. Also nitrogen with a corresponding percentage of oxygen may be used.

5 10 I claim:

10 15 1. A plant for the manufacture of bronze powders comprising, in combination, a comminuting machine, a machine for polishing the comminuted metal particles, a conduit between said machines

15 20 25 30 15 for conducting the metal particles directly from said comminuting machine to said polishing machine, and means including air tight connections between said conduit and said machines to prevent uncontrolled contact of atmospheric air with the metal particles while in said machines and said conduit, and means for supplying oxygen in regulated amount to said polishing machine.

2. The method of manufacturing bronze powders which comprises comminuting metal while substantially excluding atmospheric air therefrom, conducting the comminuted metal, while excluding atmospheric air from contact therewith, to a polishing means, and polishing the comminuted metal while subjecting the same to contact with oxygen in amount only sufficient to produce a thin oxide film on the metal particles.

3. A plant for the manufacture of bronze powders comprising in combination, a comminuting machine, a machine for polishing the comminuted metal particles, a conduit between said machines for conducting the metal particles from said comminuting machine to said polishing machine, a separator included in said conduit, means including air-tight connections between said conduit, said separator and said machines to prevent uncontrolled contact of atmospheric air with the metal particles while in said machines, said separator and said conduit, and means for supplying oxygen in regulated amount to said polishing machine.

4. The combination as specified in claim 3, including a sifter operatively connected with the discharge end of said comminuting machine and interposed between said comminuting machine and said separator, and air-tight packings in the connections between said comminuting machine and said sifter.

5. The combination as specified in claim 3, including a sifter operatively connected with the discharge end of said comminuting machine and interposed between said comminuting machine and said separator, air-tight packings in the connections between said comminuting machines and said sifter, and a fan interposed between said separator and the inlet end of said comminuting machine.
